Application April 12, 1938, Serial No. 201,536
In Great Britain May 10, 1937

6 Claims. (Cl. 178—44)

The present invention relates to reactive coupling devices and arrangements such as transformers, more especially for use in radio systems.

The invention is primarily intended for application to wireless receivers of the superheterodyne type.

In superheterodyne receivers it is known to vary the selectivity of the receiver by varying the coupling between tuned stages of the receiver, by means of a transformer coupling the two stages, the two coils of which are moved relatively to each other to vary the tuning. It is also known to vary the selectivity of the receiver by varying a capacitive coupling between tuned stages. Both these methods of selectivity variation also produce a variation in the reactances of the coupled circuits and consequently of the tuning thereof, the effect of which can be eliminated only by providing sensitive compensating arrangements which may have to be included in circuits subjected to high alternating current voltage, and are, in any case, expensive.

The object of the present invention is to provide a device for coupling a tuned circuit reactively to another circuit, wherein inexpensive means may be used for varying the coupling of the circuit and for maintaining the tuning of the circuit constant.

A further object of the invention is to provide compensating means for maintaining the damping of coupled tuned circuits constant notwithstanding a variation in the coupling between them, which means are not subjected to high alternating current voltages and may be made up in an inexpensive manner and without using expensive components.

According to the invention, a device for coupling a tuned circuit to another circuit is provided comprising means for varying the reactive linkage between the circuits by a predetermined amount, there being associated with the coupling, but not directly connected in the coupled circuits, a coil or coils adapted to be open-circuited or short-circuited as the case may be, to vary the reactance of the tuned circuit or circuits in such manner as substantially to compensate for the change in the effective reactance thereof when said coupling is varied, whereby the resonant frequency of one or both of the tuned circuit or circuits may be maintained at substantially constant value notwithstanding the change in the degree of coupling between them.

The invention may be applied, for example, to coupled tuned circuits in the intermediate frequency stage of a superheterodyne receiver, in

which, for example, inductively linked coils, one included in each of the circuits to be coupled, are wound on a former, there being provided between these coils a further coil which is connected in a circuit which may be opened or closed so that the effective coupling between the two first mentioned coils, is varied. With such an arrangement, the modification of the degree of coupling by the variation of the circuit of the third coil as above described, causes a variation in the effective inductance of the coupled coils, so that the variation in the degree of coupling causes a variation in the tuning of the coupled circuits.

In one embodiment of the invention, two coils are provided, one associated with the primary and one with the secondary side of the transformer, said coils being included in circuits adapted to be short or open-circuited according to whether the above described third coil is open or short-circuited. The short or open-circuiting of these additional coils as the said third coil is open or short-circuited, maintains the effective inductances of the linked coils in the circuits to be coupled substantially constant, thus maintaining the tuning frequencies of the coupled circuits substantially constant. If desired, only one correcting coil may be provided.

The invention is not only applicable to circuits coupled through a transformer, but may be applied in cases where circuits are wholly or partly coupled through a variable capacitative or self-inductive reactance.

The nature of the invention and the method of carrying the invention into effect will be clearly understood from the following description with reference to the accompanying drawing in which:

Fig. 1 is a diagrammatic view of a coupling device according to the invention.

Fig. 2 is a series of attenuation-frequency curves drawn to illustrate the operation of an arrangement according to the invention, and

Figs. 3 and 4 are schematic diagrams illustrating two further embodiments of the invention.

Referring to Fig. 1, it will be seen that the arrangement therein shown comprises a coupling device comprising two coils 1 and 2, respectively, adapted to be connected in the circuits to be coupled, so that one coil acts as the primary winding of a transformer, and the other as the secondary winding adjacent each other on the same former 3. Between the coils 1 and 2 is arranged a coil 4 which may be short circuited by closing switch 5. When the coil 4 is open-circuited it exerts substantially no action on the coils 1 and 2, but when the coil 4 is short-circuited it acts

as a conductive screen between the coils 1 and 2 thus reducing the degree of coupling therebetween. The width of the pass-band on the circuits associated with coils 1 and 2 is thus varied by open and short-circuiting coil 4. Further, coil 4, also acts on the coils 1 and 2 considered separately, as well as on the degree of coupling between them, and changes the effective inductances of these coils as regards the circuits in which they are located. Consequently, the resonant frequencies of those tuned circuits are caused to vary. In order to overcome this drawback according to the invention, coils 6 and 7 are provided arranged in circuits with switches 8 and 9 similar to the switch 5, one of the coils 6 and 7 being in association with the coil 1 and the other being in association with the coil 2, for example, by being arranged on the same former 3 as the coils 1 and 2, as shown. The correcting coil 6 which is associated with the coil 1 is disposed on the side of the coil 1 away from the coil 2, and likewise the correcting coil 7 is disposed on the side of the coil 2 away from the coil 1 so that neither coil 6 or 7 has any substantial effect on the coupling between the coils, but the coils are arranged so that they are linked to the coils 1 and 2 respectively in such a way that by open or short-circuiting the coils 6 and 7 an equal and opposite change in effective inductance of the coils 1 and 2 respectively is effected to cancel the change in effective inductance of the said coils due to short or open-circuiting the circuit of the coil 4. Briefly, the coils 6 and 7 introduce a detuning effect equal and opposite to that inadvertently introduced by the coil 4. Preferably, switches 5, 8 and 9 are gang controlled so that coils 6 and 7 are open-circuited automatically when coil 4 is short circuited or vice versa. For example, as shown in Fig. 1, switches 5, 8 and 9 may be linked to the same operating handle 10 in such a way that when the operating handle is actuated to close switch 5, switches 8 and 9 are opened or vice versa.

The method of operation of the arrangement of Fig. 1 will be clearly understood from Fig. 2 in which attenuation over the coupled tuned circuits is represented vertically and frequency horizontally. The mid-frequency of the band passed by the coupled tuned circuits is represented by the vertical arrow OA in the centre of the figure. When the coil 4 is short-circuited, the attenuation over the circuits will be as indicated by the full-line curve 20, the point of minimum attenuation in the curve being at the mid-band frequency. When the coil 4 is open circuited the degree of coupling between the two circuits will be increased and the bandwidth of the circuit will be broadened and humps may tend to appear in it, in known manner, as the coupling becomes tighter. Moreover as the tuning of the circuits is modified by open-circuiting the coil 4, as above explained, the resonance curve of the receiver would become unsymmetrical about the line OA as indicated by the dotted curve 21. However, by the provision of coils 6 and 7 according to the invention, the tuning frequencies of the coupled circuits are maintained constant notwithstanding the variation in the coupling between them and the selectivity curve with increased coupling remains symmetrical about the line OA as indicated by the chain dotted curve 22, and moreover, the damping of the circuits remains substantially unaltered. If desired, only one of the coils 6 and 7 may be provided, and by dimension of

this coil, nearly the same action may be reached.

The auxiliary coils 4, 6 and 7 may be of single layer or multi-layer type. The switching in of the correcting coils 6 and 7 may also cause damping of the tuned circuits and thus flatten out the double hump in the characteristic produced by increase of coupling.

Fig. 3 shows an arrangement according to the invention in which the coupling between the tuned circuits comprising the coils 1 and 2, tuned by condensers 1a and 2a respectively, is effected wholly or partly by a top or series capacity element 25 which may be cut out of circuit by a switch such as 26 or may have an additional capacitance in parallel such as 27, shown dotted, associated with a switch 28, so that upon actuation of the switch 26 or 28 the degree of coupling between the coupled circuits can be changed. This change in the coupling between the circuits also tends to cause a variation in the tuning frequencies of the circuits, and in order to compensate for this, arrangements including coils 6 and 7 associated with coils 1 and 2, as described in connection with Fig. 1 are provided.

The invention is also applicable to the case of arrangements which are coupled by a bottom condenser for example, as shown in Fig. 4, which shows an arrangement adapted to be inserted in place of or as well as the part of Fig. 3 included in the chain dotted rectangle V. The coupling element of Fig. 4 consists of a condenser or capacitance 30 with an element 31 in parallel which may be cut into or out of circuit by means of switch 32. The arrangement of Fig. 4 might be connected between the condensers 1a and 2a and earth instead of between the coils 1 and 2 as represented.

If desired, elements having substantially only self-inductance might be used instead of capacity elements in couplings treated according to the invention.

What I claim is:

1. A coupling between two circuits, at least one of which is tuned, comprising means for varying the reactive linkage between the circuits by a predetermined amount, a coil adapted to be open-circuited or short-circuited as the case may be, and inductively coupled to the tuned circuit to vary the reactance thereof in such manner as substantially to compensate for the change in the effective reactance thereof when said coupling is varied, whereby the resonant frequency of the tuned circuit may be maintained at substantially constant value notwithstanding the change in the degree of coupling between the circuits.

2. A coupling arrangement between a pair of tunable circuits comprising inductively linked coils, wound on a former, two of which coils are inductively linked together and are adapted to be included one in each of the turnable circuits to be coupled, a third coil arranged between said two circuit coils adapted to be open or short circuited to determine the inductive linkage between said two coils, and further coils each arranged on the former adjacent to and inductively linked one with each of the two first mentioned coils, said further coils being adapted to be short or open-circuited according as said third coil is open or short-circuited as the case may be to vary the reactance of the coupled circuits in such a way that the reactances determining the tuning of the coupled circuits remain constant, notwithstanding the degree of coupling there between.

3. A coupling between two tuned circuits ac-

cording to claim 1 in which the tuned circuits each including a tuning coil are variably capacitively coupled, each of said tuning coils having inductively associated with it a coil adapted to be open-circuited or short-circuited as the case may be, to vary the reactance of the tuned circuits in such manner as substantially to compensate for the change in the effective reactance thereof to maintain the tuning frequency substantially constant when said coupling is varied.

4. The combination with two circuits, each having a natural resonant frequency, and a reactive coupling between said circuits, of reactive means for varying the coefficient of coupling between said circuits, said reactive varying means tending to change the natural resonant frequency of each circuit with variation in coupling therebetween, and means including a coil inductively coupled to at least one of said circuits and adapted to be selectively open-circuited or short-circuited for compensating for said change in natural resonant frequency.

5. The combination with a pair of inductively coupled tunable circuits, of a coil associated with the inductances of said circuits, such that with the coil short-circuited the tunable circuits are loosely coupled and with the said coil open-circuited the circuits are closely coupled, said cir-

cuits tending to change their natural resonant frequency with variation in coupling from loose to close coupling relation, and means including a coil inductively coupled to the inductance of each circuit and adapted to be selectively open-circuited or short-circuited for compensating for said change in natural resonant frequency.

6. The combination with a pair of tuned circuits having main reactances in coupled relation, of means for varying the coefficient of coupling between said reactances, said means comprising a common auxiliary inductance which is adapted when short-circuited to provide loose coupling and when open-circuited to provide close coupling between said circuits, said circuits tending to change their natural resonant frequency with change from loose to close coupling, separate means associated with each main reactance for compensating for said change in natural resonant frequency, said separate compensating means comprising an inductance and a switch for selectively short-circuiting and open-circuiting said inductance, and common control means for short-circuiting the separate compensating inductances simultaneously with the open-circuiting of the auxiliary coupling-varying inductance, and vice versa.

ALEXANDER LANDMANN.
